UNITED STATES PATENT OFFICE.

FREDERICK C. SMITH, OF MARION, OHIO.

FOOT-THROTTLE MECHANISM.

1,295,380.

Specification of Letters Patent. Patented Feb. 25, 1919.

Application filed March 14, 1917. Serial No. 154,645.

To all whom it may concern:

Be it known that I, FREDERICK C. SMITH, a citizen of the United States, residing at Marion, in the county of Marion and State 5 of Ohio, have invented certain new and useful Improvements in Foot-Throttle Mechanism, of which the following is a specification.

My invention relates to foot throttle controlling mechanism for regulating the supply of fuel to automobile engines. The mechanism as designed is arranged to insure a steady supply of fuel at all times and of the quantity necessary to operate the engine.

15 The object of my invention is to provide a device which operates in conjunction with the ordinary foot throttle as usually installed and to prevent variation in pressure on the foot throttle in order to maintain the 20 supply of fuel constant. The device comprises a foot pedal or rest which is provided with a pivoted bearing preferably located between the heel and toe portion of the foot plate associated with and forming part 25 of the pedal mechanism. When the foot pedal is pressed forward the foot throttle is operated thereby allowing the fuel to be supplied to the engine. The foot pedal is provided with a suitable friction device 30 sufficient to overcome the tension of the foot throttle thereby holding it in any desired position.

The particular object of my invention is the design of the foot plate itself which is 35 arranged to accommodate the shoe of drivers which may be of different shape. The foot plate is designed to receive the shoe of a man or woman so that the foot remains in a natural resting position when driving the 40 car. In operating the car and in order to supply but a small amount of fuel the pedal is operated in a forward position to a certain degree and in order to increase the supply of fuel the forward movement is increased. If it is so desired the foot can be 45 removed from the pedal which will maintain its position and cause the proper amount of fuel to be supplied. Ordinarily in driving over rough roads a certain amount of vibration is extended to the foot of the driver thereby causing an uneven flow of fuel when operating the ordinary foot throttle. With the device as outlined however, the variations are taken up and the foot remains in 55 a natural position.

The foot plate at the heel portion is pro-

vided with a recess or rest for accommodating the heel of a woman's shoe. The flange or portion surrounding the recess is arranged to receive the heel of a man's shoe. 60 Both the heel and toe portions are provided with extending flanges to prevent the foot slipping from the plate.

My invention is illustrated in the accompanying drawings wherein:

Figure 1 is a side view showing the assembled device.

Fig. 2 is a bottom plan view showing a foot plate and an adjustable support.

Fig. 3 is an end view of Fig. 1 looking toward the toe portion of the device.

Fig. 4 is a top plan view of Fig. 2.

Fig. 5 is a modification of a foot plate shown in Figs. 1, 2, 3 and 4 wherein a recess is provided for receiving the heel of a woman's shoe.

Fig. 6 is a side view of Fig. 5.

Referring to Figs. 1, 2 and 3, the foot plate 5 is provided with a tongue or angle portion 4 fastened to the underside of the 80 foot plate. This portion 4 is adapted to engage the head 40 of the foot throttle 41.

The foot plate 5 is formed with a recess 56 extending entirely across the heel portion. The plate is also provided with the arch 85 support 54 and with the raised flanges 2 and 3.

The plate 5 is provided with the adjustable bearing 44 fastened to the plate by means of the bolts and nuts 45. As shown in Fig. 90 2 this support is provided with the slots 70 so as to allow longitudinal adjustment of the foot plate 5. The bearing 44 is provided with a tongue or extension 49 provided with an opening through which the bolt 51 passes. 95 This bolt engages the slot 53 of the friction disk 52 which is held in place by means of the bolt and nut 57. This friction device is fastened to the under bearing 55, fastened to the floor of the car 50 between the bearing 55 and the friction disk 52 is a fiber washer 75. This fiber washer is held in place by means of the bolt 57 which engages the support 55.

The adjustable bearing 44 rocks upon a 105 bolt 48 which passes through the support 42 as shown in Figs. 1 and 2. This bolt is held in place by means of the nut 47.

In operating the device the foot plate rocks upon the bolt 48 supported by the 110 bearing 42 which is mounted upon the upper surface of the floor of the car by means of

the screws or bolts 43. In rocking the pedal or foot plate sufficient pressure has to be used to overcome the tension of the friction bearing 52 which binds against the support 55.

5 In addition to the fiber washer acting as a friction device a spiral spring of sufficient tension can also be added to cause the disk 52 to bear against the bearing 55. (Such a spring is shown in my pending application, Serial No. 126,670, filed October 20, 1916.) The tension can then be readily increased by turning the bolt 58.

10 It will be noted that the foot plate 5 is provided with the recess 56 for accommodating the heel of a woman's shoe. When a man is operating the device, however, the heel of his shoe will extend over the recess 55.

15 20 Referring to Fig. 4, a top plan view is shown of the foot plate of Figs. 1 and 2. This view plainly shows the raised flanges 2 for preventing the toe of the shoe from slipping from the plate.

25 30 Referring to Figs. 5 and 6, it will be noted that the heel portion is provided with a recess 61 which is formed by pressing in the metal of the plate. This form of foot plate can readily be fastened in place of that shown in Figs. 1 and 2, as the openings 65 and 66 are arranged to coöperate with the bolts and nuts 45.

35 From the foregoing description it will be noted that the foot plate is provided with a plurality of heel rests to accommodate the heels of different shaped shoes.

This arrangement is made to allow the

pressure of the foot of the various drivers to bear the same relation to the pivot bearing upon which the plate rocks.

Having thus described my invention what 40 I desire to secure by Letters Patent is:

1. A foot plate comprising a heel and toe portion, an adjustable bearing for said plate situated between the heel and toe portion and upon which the plate rocks, a heel rest at the heel portion of the plate comprising a recess and an additional heel rest comprising an extended portion provided with flanges. 45

2. A foot plate provided with a central bearing upon which it rocks, the rear end of said plate being provided with heel rests consisting of a recess and an extended portion provided with flanges. 50

3. A foot throttle controlling mechanism, comprising a foot plate provided with a heel and toe portion, said heel portion being provided with a supporting surface and a recess, said surface and said recess serving to 55 support the heel of a shoe.

4. A foot throttle controlling mechanism, comprising a foot plate provided with a heel portion, said heel portion being provided with a heel supporting surface and an additional heel supporting portion formed by a depression in said bearing surface. 60 65

In testimony whereof I affix my signature in the presence of two witnesses.

FREDERICK C. SMITH.
